UNITED STATES PATENT OFFICE.

WILLIAM C. BRYCE, OF MONTREAL, QUEBEC, CANADA.

STRAIGHTWAY DRY-PIPE VALVE.

1,200,307.

Specification of Letters Patent.

Patented Oct. 3, 1916.

Application filed May 18, 1916. Serial No. 98,357.

To all whom it may concern:

Be it known that I, WILLIAM C. BRYCE, a subject of the King of Great Britain, residing at Montreal, in the Province of Quebec, Dominion of Canada, have invented new and useful Improvements in Straightway Dry-Pipe Valves, of which the following is a specification.

The invention to be hereinafter described relates to straightway dry pipe valves.

In order to more clearly disclose the construction, operation, and use of the invention, reference should be had to the accompanying drawings forming part of the present application.

The single figure of the drawings is a central vertical cross section, the full line position showing the valve as closed and the dotted line position showing it as open.

Broadly speaking, there are two types of dry-pipe valves in general use at the present time, known, respectively, as the differential and the mechanical. A brief general disclosure of each will help to give a fuller conception of the present invention and the objects at which it aims. In the differential type there is a double seated valve, having an upper or air seat of much greater area than its lower or water seat. The difference in area between the two seats determines the differential or difference in pressure necessary to balance the valve. This is usually in the ratio of about 7 to 1—one pound air pressure balancing seven pounds of water pressure. In the mechanical type the main water valve is held closed by a system of levers and weights which are held in place by the action of air pressure on a small air valve. The trip point of a mechanical valve is practically constant and is determined by the tension on the adjusting screw. The differential type of dry-pipe valve is considered more satisfactory than the mechanical type, but it is objectionable on account of its bulk which results from the fact that the air seat must be approximately seven times the area of the water seat, and because of the danger of water columning if the valve opens under very low pressure.

The main object of the present invention is to provide a straightway dry-pipe valve which is, in effect, a differential, but in which there is no valve of greater area than the main water valve. In former inventions I obtained this result by a by-pass around

the main water valve, and a smaller valve in the by-pass, with levers connecting the valves so that when the by-pass valve was in position it held the main water valve in place. In those former inventions, the main water valve opened directly into the air system and this is considered objectionable. It is considered advisable to have an intermediate chamber between the wet system below the dry-pipe valve and the air system above it.

Broadly speaking, the present invention includes an intermediate chamber between the main water valve and the air valve, an air valve above the intermediate chamber, a lever mounted in the intermediate chamber, oppositely acting valves carried by said lever at opposite sides of its fulcrum and controlling the main water inlet and by-pass inlet, respectively, and connections between the air valve and the valve controlling the main water inlet.

The casing containing the entire operating mechanism consists, preferably, of two castings or sections 1 and 2. The section 1 is provided with the inlet connection 3 leading from the water main, and the by-pass section 4 leading from the inlet connection. The inner end of the by-pass is provided with a valve seat 5 threaded thereinto and adapted to seat or receive the by-pass valve 6 carried on the outer end of an arcuate arm 7 from which extends a shorter arcuate arm 8, pivotally mounted on a pin 9 in the walls of the section 1. At the point of junction, arms 7 and 8 are enlarged and bored out, as at 10, and internally threaded, to receive a threaded rod 11, having a ball and socket connection between its lower end and a main water valve 12, controlling the main water inlet. The upper end is provided with a bolt head 13, having a conical tip 14, for a purpose to be later disclosed. The arms 7 and 8 constitute an elbow lever which is fulcrumed at a point substantially mid-way between the valves 6 and 12, carried by its opposite extremities and seating in opposite directions. The valves and leverages are so proportioned that the force operating on the main water inlet valve is slightly greater than that operating on the by-pass valve. Since the two valves are on opposite ends of the same lever and operate in opposite directions, the tendency is for the main water inlet valve to fly open. To prevent this, the

air valve 19 is used. It is directly above the main water valve and on the same center line, providing a straight water way. It is pivoted at one side of the inlet leading from the valve chamber into the air chamber 20, and the air chamber is enlarged at that side as at 21, to permit the air valve to swing back completely out of the path of the incoming current of water, as in the dotted line position. The lower face of the air valve is provided with an internally threaded boss 18 to receive an adjusting bolt 17 which is provided with a nut head 16 having a conical socket 15 to receive the conical tip 14. By-pass valve and levers are so proportioned, relatively to the areas of valves 12 and 19, that the pressure on 19 bears the ratio of 7 to 1 as compared to the resultant pressure on the balanced valve, 20 when the system is in operation.

Hand holes 22, 23, and 24 are provided for access to the operating parts and a small outlet 25 is provided in section 1 just about on a level with the main water inlet. 25 This permits the escape of any slight leakage should that occur, but is more especially provided to allow entrance of air so that atmospheric pressure will be maintained within the valve chamber.

30 In setting the valve, the elbow lever will be swung on its fulcrum until valve 6 is accurately seated, then, if valve 12 is not quite accurately seated, the rod 11 will be rotated until the valve does accurately seat. 35 Next, the air valve will be swung toward its full line position so that conical tip 14 enters socket 15. Then the air is pumped in above valve 19. Then the bolt 17 will be rotated until there is a slight tension. And, 40 finally, water is turned on from the main below the balanced valve. When the air pressure is reduced below the predetermined point, the water pressure kicks valve 12 open and drives valve 19 to its dotted line 45 position as it rushes into the system. Valve 6 gravitates to the dotted line position and maintains valve 12 in its dotted line position. Thus, all valves are kept completely 50 out of the path of the incoming current of water and there is provided a straight water way with no danger of water columning. As will be seen, the swing of valve 6 through by-pass 4 has a dash pot effect which slightly cushions the downward swing.

55 Adjustment of valve 12 is necessary only occasionally to compensate for wear, after the first regulation.

Among the objects attained by the present invention are, a straight water way, simplicity, lightness of construction, efficiency, compactness, durability, and absolute certainty of automatic operation.

It is thought that the construction, operation, and use of the invention will be clear 60 from the preceding detailed description.

Changes may be made in the construction, arrangement, and disposition of the several parts of the invention without in any way departing from the field and scope of the same and it is meant to include all such 70 within this application, wherein only a preferred form has been disclosed.

Having thus described my invention, what I claim and desire to protect by Letters Patent of the United States is:—

75 1. In straightway dry-pipe valve mechanism, a casing containing an upper air chamber having an outlet and a lower valve chamber having two inlets, in combination with an air valve controlling communication between said chambers, a main-inlet pipe connected to one of said inlets, a by-pass extending from this main-inlet pipe to the other inlet, a lever arranged in said valve chamber and provided with two arms 80 extending in opposite directions, one from its fulcrum point and the other from the extremity of the first arm and two inlet valves attached to said arms respectively, one of these valves closing down on the main 85 inlet and the other valve closing up against the by-pass inlet and cushioned by the press of water up within said by-pass when the opening of the main inlet valve forces said by-pass valve down through said by-pass. 90 95

2. In straightway dry-pipe valve mechanism, a casing containing an air-chamber having an outlet, a valve chamber below said air chamber and a main water inlet and by-pass water inlet in the bottom of said valve 100 chamber, in combination with a main-inlet pipe connected to said main inlet, a by-pass extending from said main-inlet pipe to said by-pass inlet, an air-valve controlling passage from said valve chamber to said air 105 chamber, a main inlet valve closing said main inlet, a by-pass valve operating reversely to said main inlet valve, a lever in said valve chamber provided with arms which carry respectively the two latter 110 valves arranged so that one of these valves will partly balance the other under pressure.

3. In straightway dry-pipe valve mechanism, an air chamber having an outlet, a valve chamber below said air chamber, communicating therewith and provided with a main water inlet and a by-pass inlet, in combination with valves for said inlets and a lever to which they are attached so that the pressure on the by-pass valve partly balances the pressure on the main inlet valve, a main inlet pipe and by-pass connected with said inlets respectively, an adjusting device for the main-inlet valve acting on said lever, a hinged air valve closing communication between said air chamber and said valve chamber, and a device carried by said valve and bearing in its closed position on said adjustable device. 115 120 125

4. In straightway dry-pipe mechanism, an 130

- air chamber and a valve chamber communicating therewith and having two inlets, a lever in said valve chamber carrying two valves arranged to close said inlets and to 5 act in opposition to each other, an air valve closing communication between the said chambers, a depending part connected to said valve and adjustable toward and from the latter and a part mounted on said lever 10 against which said adjustable part bears in its lowest position.
5. In straightway dry-pipe valve mechanism, an air chamber having an outlet and a valve chamber communicating with said 15 air chamber and having two water inlets, in combination with an air valve in said air chamber closing communication between the two chambers, an adjustable bolt depending from said valve and provided with 20 a conoidal recess in its head, a rod having a conoidal head for entering said recess and making contact without positive connection, a pair of valves for closing the water inlets and a lever having said rod and pair of 25 valves attached thereto, these valves and lever being arranged for said valves to act in opposition to each other in order that the pressure on the air valve may need to resist only the amount of pressure on one of 30 said inlet valves in excess of the pressure on the other inlet valve.
6. In straightway dry-pipe valve mechanism, a casing containing two communicating chambers, the upper being an air chamber 35 provided with an outlet and the lower being a valve chamber provided with two inlets, in combination with a valve in said air chamber closing communication between the two chambers, a lever pivoted in said 40 valve chamber and provided with an arcuate arm to which a valve is attached for closing one of said inlets, another arm extending in the opposite direction from its fulcrum, and secured to the end of the first 45 mentioned arm remote from its valve, a valve closing the other inlet and an adjustable device suspending the last named valve from the latter arm, these inlet valves operating in opposition to each other.
- 50 7. In straightway dry-pipe valve mecha-
- nism, a casing containing an air chamber having an outlet and a communicating lower valve chamber having two inlets, a pair of inlet valves and connected means whereby these valves close said inlets, acting in opposition to each other, and an air valve closing communication between said chambers and resting on said means above one of said inlet valves but without connection with said means or said valve. 55
8. A straightway dry-pipe valve comprising, a casing having a valve chamber provided with main and by-pass inlets, a main inlet pipe, a by-pass leading from this pipe to the by-pass inlet, and an air chamber with 60 an inlet communicating with said valve chamber, an elbow lever fulcrumed in side valve chamber at a point between said by-pass inlet and said main inlet and provided with an enlargement at its elbow, said enlargement being provided with a longitudinal bore, a rod adjustable in said bore, a main inlet valve carried thereby, a by-pass valve carried by said elbow lever at the opposite side of its fulcrum and an air valve 65 in said air chamber, connected to said rod.
9. A straightway dry-pipe valve comprising, a casing having a valve chamber provided with main and by-pass inlets, a main inlet pipe, a by-pass leading from this pipe to the by-pass inlet, and an air chamber with 70 an inlet communicating with said valve chamber, an elbow lever fulcrumed in said valve chamber at a point between said by-pass inlet and said main inlet and provided with an enlargement at its elbow, said enlargement being provided with a longitudinal bore, a rod adjustable in said bore and provided with a conical tip, a main inlet valve carried by said rod, a by-pass valve 75 carried by said elbow lever at the opposite side of its fulcrum, an air valve in said air chamber, and an adjusting bolt carried by said air valve and provided with a bolt head having a socket to receive the afore- 80 said conical tip of the rod of the main inlet valve. 85
